(57) **CLAIM**

The housing for communication device or similar articles, as shown.

DESCRIPTION

FIG. 1 is a front, bottom and side perspective view of an ornamental design for a housing for a communication device or similar articles.

FIG. 2 is a front orthogonal view of FIG. 1.

FIG. 3 is a back orthogonal view of FIG. 1.

FIG. 4 is a first side orthogonal view of FIG. 1.

FIG. 5 is second side orthogonal view of FIG. 1.

FIG. 6 is a top orthogonal view of FIG. 1; and,

FIG. 7 is a bottom orthogonal view of FIG. 1.

The broken line portions of the drawings form no part of the claimed design.

1 Claim, 4 Drawing Sheets
